UNITED STATES PATENT OFFICE.

GLENN H. CURTISS, OF BUFFALO, NEW YORK.

DESIGN FOR AN AEROPLANE.

55,504.

Specification for Design. **Patented June 22, 1920.**

Application filed February 17, 1917. Serial No. 149,369. Term of patent 14 years.

To all whom it may concern:

Be it known that I, GLENN H. CURTISS, a citizen of the United States, residing at Buffalo, in the county of Erie and State of New York, have invented a new, original, and ornamental Design for an Aeroplane, of which the following is a specification, reference being had to the accompanying drawings, forming part thereof.

Figure 1 is a side elevation of the body;

Fig. 2 is a front end elevation, and

Fig. 3 is a top plan view.

The invention resides in the ornamental

features of a combined road and air vehicle comprising supporting planes or aerofoils arranged with an automobile body of the Sedan type, the arrangement of the supporting planes with respect to the body being substantially as shown in the drawings.

I claim:

The ornamental design for an aeroplane as shown and described.

GLENN H. CURTISS.
